CAVITY RESONATOR HIGH-FREQUENCY APPARATUS

Lloyd P. Smith, Ithaca, N. Y., assignor to Radio Corporation of America, a corporation of Delaware

Continuation of application Serial No. 563,732, November 16, 1944. This application May 2, 1952, Serial No. 285,627

35 Claims. (Cl. 315—5)

This application is a continuation of my copending application Serial No. 563,732, filed November 16, 1944, assigned to the same assignee, now abandoned.

My invention relates to generators of high frequency radio waves using cavity resonators and more particularly to electron discharge devices such as magnetrons utilizing cavity resonators and to a method and means for varying the generated frequency.

It has become necessary to be able to vary the generated frequency over a limited frequency range of a magnetron or other ultra high frequency generator using cavity resonators as tank circuits. It is desirable to have the frequency change occur as a prescribed function of the time and with greater rapidity than is practical by mechanical tuning of the resonator. It is further desirable that the power output should be constant over the variable frequency range.

It is, therefore, an object of my invention to provide a high frequency generator utilizing a cavity resonator and a means for varying or modulating the generated frequency.

Another object of my invention is to provide an electronic device using a cavity resonator and which can be utilized as a variable reactance device when coupled to a high frequency system.

A still further object of my invention is to provide an electron discharge device utilizing cavity resonators which can be frequency modulated.

More specifically it is an object of my invention to provide a magnetron utilizing one or more cavity resonators and which can be frequency modulated by electronic means.

The novel features which I believe to be characteristic of my invention are set forth with particularity in the appended claims, but the invention itself will be best understood by reference to the following description taken in connection with the accompanying drawing in which Figures 2, 3 and 4 are diagrams which help to explain the principles of my invention, Figure 1 is a perspective view with parts broken away of one embodiment of my invention, Figures 5 and 6 are equivalent circuits showing operation of apparatus made according to my invention, Figure 7 is a graph illustrating the operation of a device made according to my invention, Figure 8 is a plan view of a magnetron incorporating my invention, Figure 9 is a section taken along the line IX—IX of Figure 11, Figure 10 is a section taken along the line X—X of Figure 8, Figure 11 is a side view of the magnetron shown in Figure 8 with part of the shell removed, and Figure 12 is a section taken along the line XII—XII of Figure 11.

The method and apparatus employing my invention can best be understood by reference to Figure 1 which utilizes a cavity resonator, the resonant frequency of which can be changed by electronic means.

In the device shown I provide an evacuated envelope 10 containing a rectangular cavity resonator 11 having dimensions X, Y and Z. The cavity resonator is provided with oppositely disposed apertures 12 and 13 in opposite walls thereof through which an electron beam is directed. The electron beam is provided by means of the indirectly heated cathode 14 and can be controlled by the grid 15. The electrode 16 on the opposite side of the resonator and in the path of the electron beam may be used in place of or in combination with the grid 15. Transfer of energy to and from the cavity resonator 11 may be had by means of the coaxial line 17 coupled to the resonator 11 by a loop 17' coupled to the interior of the resonator. A constant

2

magnetic field H is established along the path of the beam of electrons by means of a magnet having pole pieces 18 and 19. A control input circuit includes the transformer 20 and the voltage sources include the grid biasing voltage source 21, cathode heater voltage source 22, voltage source 23 for applying a positive potential to the resonator 11 and voltage source 24 which may apply either a positive or negative voltage to the electrode 16, depending upon whether the electrode is to be used as a collector or reflector. Alternative arrangements for controlling the beam include the circuit having the transformer 25 for applying varying accelerating voltages to resonator 11 and the circuit including the transformer 25' connected to the electrode 16 for varying the voltage applied to this electrode when used as a control electrode to reflect electrons back into the resonator.

In order to set up an alternating electric field within the resonator some form of driving means is necessary. In the arrangement shown a cavity resonator magnetron generator 26 whose frequency is to be controlled is used as the driver. The magnetron 26 is provided with a cathode 27 and radially directed fin-like elements 28, the inner edges of which provide the anode segments. The wall of the envelope of the magnetron, which is a metallic envelope, and the fins or slats 28 form the cavity resonators between adjacent anode segments. This form of magnetron is well-known. A magnetic field is provided parallel to the cathode in the space between the cathode and the anode segments. The coaxial line 17 has a coupling loop 29 coupled to one of the magnetron resonators between adjacent anode segments. The coupling loop 17' of coaxial line 17 is oriented within the resonator 11 in a plane perpendicular to the beam path therein, so that a high frequency electric field E in the direction indicated is established therein.

The resonator 11 serves as a magnetron pilot cavity resonator for varying the resonant frequency of the magnetron 26 to which it is coupled.

The constant magnetic field along the Z direction of the resonator 11 serves two purposes. It keeps the electron beam together and it is by means of this magnetic field that electrons are made to move in such a way as to produce a large reactive current in the interior of the cavity resonator. The cavity resonator is assumed to be excited at an angular frequency ω , with no electron beam present, for example, by the magnetron 26, although it could be excited by other means. This frequency corresponds to the normal mode of oscillation for which the electric field is always parallel to the X direction of the resonator, that is, transverse to the direction of the electron beam. When an electron moves in a uniform transverse magnetic field H it will follow a circular path. The time T required to traverse a complete cycle or circle is

$$T = \frac{2\pi m}{He}$$

where π is 3.1416, m is the mass of an electron e is its charge and H is the magnetic field intensity. Hence, this period of rotation is independent of both the linear velocity of the electron and the radius of its circular path. The angular frequency of rotation of the electron is then

$$\omega_0 = \frac{2\pi}{T} = \frac{He}{m}$$

When an electron beam is made to traverse the cavity resonator 11 the resonant angular frequency of the resonator in the particular mode of oscillation under consideration changes from ω to $\omega + \Delta\omega$, where $\Delta\omega$ depends upon the beam current, the transit angle of the electrons through the resonator, and the magnetic field strength. The magnitude of the frequency shift $\Delta\omega$ may be readily computed from developed formulas.

It has been found that, in the case of the rectangular cavity resonator $\Delta\omega$ is proportional to the total beam current I and inversely proportional to the volume XYZ of the cavity resonator. For a given transit angle through the resonator not too small $\Delta\omega$ attains a maximum value for a magnetic field such that $(1-k) \approx 4$ radians, where

$$k = \frac{\omega_0}{\omega}$$

ω_0 is the electron rotation frequency defined above and where α is the transit angle in radians. The relationship $(1-k)\alpha \approx 4$ may also be written $\tau(\omega - \omega_0) \approx 4$, where τ is the electron transit time through the resonator, since α equals $\tau\omega$. The value of τ is determined by the particular beam accelerating voltage and the dimension Z of the cavity resonator. Substituting for ω and ω_0 the relationship becomes

$$\tau \left(2\pi f - \frac{He}{m} \right) \approx 4$$

where f is the operating frequency. When the magnetic field is adjusted for maximum frequency shift, the $\Delta\omega$ is proportional to the square of the transit angle α . For values of magnetic field considerably different from that necessary to produce maximum shift, $\Delta\omega$ can be shown to be proportional to α .

A better understanding of my invention may be had of the above by referring to Figures 2, 3, 4, 5 and 6.

Consider a pair of parallel plates P across which an alternating potential difference is applied resulting in an electric field of amplitude E and angular frequency ω between the condenser plates, as shown in Figure 4. The uniform magnetic field is in the direction shown. An electron is projected into the field between the plates along the dotted line ab , parallel to the magnetic field. Its linear velocity in this direction will remain constant so that at time $t=0$ the electron will be at position 1 and at time Δt seconds later it will be at position 2, etc. At position 1 the electron has no velocity in the direction of E but on encountering the electric field E between positions 1 and 2, it will be accelerated in this direction. If the angular frequency ω of the oscillating electric field E were equal to the electron rotation frequency ω_0 , each electron would remain in phase with the electric field and would be continuously accelerated so that it would receive more and more energy from the oscillating field and its motion would be a spiral of ever increasing radius. This condition would produce an electron current in phase with E at all positions, 1, 2, . . . and would constitute a loading or resistive component of current. If the condenser plates were to form a part of a resonant circuit, by connecting an inductance between the plates this resistive or in phase component would have no effect on the frequency but would reduce the Q of the circuit.

The transit time of the electron through the condenser plates from a to b and the relative values of ω and ω_0 can be chosen so that the net electron current is not in the direction of E but is in quadrature to E so that it constitutes a purely reactive current. To see how this comes about, let ω_0 be somewhat less than ω . In this circumstance the electron will not complete one revolution during one complete cycle of the oscillating field. Consequently it will lag behind E by a certain phase angle $\Delta\phi$ so that as the time goes on the electron lags more and more behind E . It will, however, continue to be accelerated until it lags behind E by 90 degrees. The electron then still increases its lagging phase angle by $\Delta\phi$ on each revolution but the electron now is retarded by the oscillating field and loses energy. It is evident that for a given value of $\omega - \omega_0$, the time of flight of the electron between the condenser plates can be adjusted so that the energy acquired from the field in the period during which acceleration took place is just given back to the field during the period of retardation and the net energy transfer from field to electron is zero. This situation is illustrated in Figures 2, 3 and 4. When an electron enters the plates at position 1, Figure 4, it has no displacement from the median plane between the plates. This zero displacement is shown in Figure 3. Also the transverse current at position 1 is zero as is shown in Figure 2. At position 2, Figure 4, the electron has acquired some spiral motion and its displacement from the median plane is shown by the vector r_2 in Figure 3. Since $\omega_0 < \omega$ the electron lags behind E by the phase angle ϕ_2 when it reaches position 2. The transverse electron current in magnitude and phase relative to E is shown by the vector i_2 in Figure 2. When the electron has reached position 3 its displacement is given by r_3 and the transverse current by i_3 . It is evident that at position 3 the magnitude of the current i_3 is greater than at position 2 as also is the lagging phase angle. At position 5, the electron has acquired its maximum displacement and the current i_5 due to it is 90° out of phase with E and is purely reactive. From this point on the electron is retarded and the current produced by it has

a negative resistive component i. e., a component opposite to E . When electrons enter the condenser plates at all times as in a continuous beam there will be electrons at all positions from 1 to 9 simultaneously and the total effective current will be the vector sum of the currents at each position. This vector sum is shown by I in Figure 2. Thus the total effective current lags behind the field E by 90°. Thus E and I are related in phase exactly the same as the potential difference across an inductance and the current through it. If the condenser plates as shown were in parallel with an inductance to form a resonant circuit with resonant frequency ω , the passage of the beam of electrons through the condenser plates would increase the resonant frequency.

On the other hand if $\omega_0 > \omega$ then the currents i_2 , i_3 , etc. would lead E and $\omega_0 - \omega$ could be so chosen that the total current would lead E by 90° giving rise to a decrease in the resonant frequency of the parallel circuit.

In effect what the above means is that when the electrons lag the alternating electric field, there is in effect an inductive reactance placed in parallel with the inductive reactance connected across the plates and the equivalent circuit is shown in Figure 5. Inasmuch as this causes a reduction in the inductive reactance of the given frequency, the inductive and capacitive reactances do not provide resonance at this frequency. The frequency of the driving voltage must be raised to bring about resonance again. This causes the capacitive reactance to decrease and the inductive reactance to increase so that resonance is established at the higher frequency. Likewise when the electrons are ahead of the electric field the resultant effect is to place a capacitance in parallel with the capacitance of the plates the equivalent circuit being shown in Fig. 6. This reduces the capacitive reactance of the resonant circuit and in order to establish resonant conditions the frequency must be lowered so that the inductive reactance decreases and the capacitive reactance increases. Thus there is provided the means for varying the resonant frequency of the system above and below that which the system would have with no electron beam present. This is the action which takes place in a cavity resonator which is the equivalent of the resonant circuit discussed.

The effect of changing the transit time of the electron through the plates can be seen from the following. Shortening the transit time for a given $\omega - \omega_0$ would have the same effect as that produced by shortening the plates. Thus if the plates were terminated at position 7 in Figure 4, the effective current between the plates would be given by the dotted vector in Figure 2. In this case the inductive component of current has been decreased and a resistive component of current is present. Hence changes in the transit time can also be used to change the frequency of a resonant system composed of the condenser plates and a parallel inductance. On the other hand, varying the current density varies the length of the resultant vector I along the X axis since each of the components i_2 to i_8 is varied. Thus the inductive reactance is in effect varied and hence the frequency.

In Figure 7 is shown the relationship of the change $\Delta\omega$ in frequency to the k ratio,

$$\frac{\omega_0}{\omega}$$

which is equal to

$$\frac{|e|H}{m\omega}$$

In this formula ω is the natural frequency of oscillation of the rectangular cavity resonator of Fig. 1 in the fundamental mode with no beam. Figure 7 gives an idea of the behavior and order of magnitude of the change in frequency $\Delta\omega$ per milliampere of beam current shown as a function of k for a 4000 megacycle rectangular resonator $Y=Z=5.3$ cm. and $X=.2$ cm., when the electrons in the beam enter the resonator after having been accelerated through 100 volts.

From the curve it will be seen that the frequency shift $\Delta\omega$ can be positive or negative depending upon whether k is less than or greater than one. Physically, as described above, this is due to the fact when k is less than one the rotating electrons tend to fall behind the electric field, thus producing the effect of a lagging current, that is inductance. On the other hand, when k is greater than one, elec-

electrons get ahead of the electric field causing a capacitance effect and the frequency decreases.

The effectiveness of a given current in changing the frequency, that is, in producing reactance, is greatest when the magnetic field is adjusted to optimum conditions for the transit time used. Using the relationship $(1-k)\alpha \approx 4$, given above the two values of the ratio k for maximum frequency shift $\Delta\omega$ for the rectangular cavity resonator XYZ described, having a dimension $Z=5.3$ cm., a resonant frequency of 4000 megacycles and a 100 volt beam, are approximately .98 and 1.02, for positive and negative frequency shifts, respectively. These values of k correspond to the maximum and minimum points on the curve shown in Fig. 7. Thus Figure 7 shows that, for the resonator described, a value of magnetic field such that the ratio k is substantially different from .98 and 1.02 causes the effect in the change of frequency to be hardly noticeable.

Thus a means is provided for markedly changing the resonant frequency of the cavity resonator by electrons when the magnetic field is suitably adjusted. The frequency can be varied as an arbitrary function of the time by varying the beam current or transit angle, or both, appropriately with the time.

As pointed out above, changing either the electron current density or the electron transit time will produce a corresponding change in the resonant frequency of the resonator 11. With no beam, i. e., zero current density, there will be no change in frequency. As the current density is increased, the frequency will be shifted more and more, in a direction determined solely by the sign of the quantity $\omega - \omega_0$. As explained above, when ω_0 is less than ω , i. e., $\omega - \omega_0$ is positive, the frequency is increased, and vice-versa. If a fixed voltage is applied to the resonator 11 and an alternating voltage applied to the grid 15 by means of the input 20, the current density is varied and hence the resonant frequency of resonator 11 is varied. If the voltage applied to the grid 15 is fixed and the accelerating voltage applied to the resonator varied by means of the input 25, the transit time of the electrons through the resonator is varied, thus again varying the resonant frequency of the resonator 11. It may also be desirable to utilize the electrode 16 merely as a reflector, sending the electrons back to the resonator to be collected in the resonator. In this case the alternating variable voltage may be applied to the reflector 16 by means of the input circuit 25'. It is, of course, understood in all these cases that magnetron 26 acts as the driver for the resonator to induce the alternating electric field in the proper mode for bringing about the action desired, the change in resonant frequency of the resonator 11 being reflected back into the resonators of the magnetron 26 to vary its frequency. Thus an electronic means is provided for frequency modulating a magnetron utilizing cavity resonators.

Thus, the tube shown in Figure 1, composed of an appropriate resonator and beam supplying means and means for controlling the beam current or the transit time, constitutes a variable reactance tube which when closely coupled to a high frequency system can be used to vary the resonant frequency of the system by introducing an almost pure inductive or capacitive reactance which can be varied with the time in any manner.

The same means of changing frequency can be incorporated in a high frequency generator to obtain a generator which can be internally frequency modulated. It is especially advantageous to apply the means explained above to frequency modulate a magnetron because arrangements can be made to use the same magnetic field used for the magnetron. Such a magnetron incorporating my invention and utilizing a multi-cavity system is shown in Figures 8 to 12 inclusive.

In this arrangement an anode block 30 is provided with a central opening 31 extending therethrough. A plurality of anode segments in the form of radially directed anode vanes 32 surround a central space in which is axially mounted an indirectly heated cathode 33. It is obvious that, instead of the flat vane type anode arrangement, the block could be provided with radial slots for obtaining anode segments, or other forms of spaces between anode segments could be provided. The slots or spaces provide the cavity resonators 32' which in the form shown are provided between adjacent anode vanes by the vanes and the wall of the opening 31 through the anode block. These various anode vanes are strapped to-

gether by means of conducting ring members 70 and 71, the rings being connected to alternate vanes, as shown in Figs. 9 and 10, to facilitate operation in the desired mode.

The cathode 33 is supported by means of the magnetic insert 34. Magnetic inserts 34 and 35 are carried by bridge members 36 and 37 mounted on the anode block 30 in insulating relationship to the block by means of bolts 38 and nuts 39, insulating sleeves 40 and 40', 41 and 41' and 62' and 62". One of the cathode heater leads 42 is connected to the insert 34 in electrical contact with the cathode sleeve 33 and the other lead 43 extends through an eyelet and is sealed through the header 45 of the envelope by means of the glass lead and seal 43'. The bridge member 36 is electrically connected to the lead 44 which extends through and is sealed in the header 45 of the envelope 55 by means of the insulating tube 44'. The anode block 30 may be supported from the header 45 by means of the supports 46 and 47. An output coupling loop 50 disposed in one of the cavity resonators 20 terminates in a coaxial line 51-52 is sealed at its end by means of the cap 53. A permanent magnet having poles 56 and 56' provides the usual magnetic field in the cathode space and in the resonators, in a direction parallel to the cathode 33.

In accordance with my invention I provide one or more indirectly heated cathode sleeves 60 supported by the insert 35 by means of the insulating collars 61, the leads 62 and 63 for the cathode and for the cathode heater extending through and sealed by tubular members 64. Insulatingly mounted on the end of each cathode sleeve 60 by means of the insulating collar 66 and supporting ring 66" is grid 66" having lead 65 sealed through the insulating member 65'. Each beam B of electrons from a cathode is directed through one of the cavity resonators towards the collector 67 also provided with a lead 68 sealed through the insulating tubular member 68'.

The operation of the internally-modulated magnetron of Figs. 8-12 is similar to that of Fig. 1, the principal difference being that the cavity resonators of the magnetron in Figs. 8-12 are excited by the space charge revolving in the anode-cathode space whereas the cavity resonator of Fig. 1 is excited by an external oscillator closely coupled thereto.

To frequency modulate the magnetron a signal may be applied to the control grid 66". As an alternative, however, the grid may be eliminated and the velocity of the electrons controlled by applying a radio frequency voltage between the anode block 30 and cathode 60. Electrode 67 may be used as a reflector in which case electrons are repelled back through the resonator and collected by the anode vanes, thus varying the transit time of the electrons through the resonator. It is obvious that one or more modulating cathodes could be utilized and that the modulating beams B could be projected through more than two resonators. The electron gun could also be replaced by an annular gun and a single collector. These are all equivalents of the arrangement shown.

The form of the invention disclosed in Figures 8 through 12 is claimed in applicant's co-pending application, Serial No. 23,045, filed April 24, 1948, which is a continuation-in-part of my copending application Serial No. 563,732, referred to above.

While I have indicated the preferred embodiments of my invention of which I am now aware and have also indicated only two specific applications for which my invention may be employed, it will be apparent that my invention is by no means limited to the exact forms illustrated or the use indicated, but that many variations may be made in the particular structure used and the purpose for which it is employed without departing from the scope of my invention as set forth in the appended claims.

What I claim is:

1. A variable frequency device including hollow resonant means normally resonant at a predetermined frequency, cathode means adjacent said hollow resonant means for directing a beam of electrons along a path within said hollow resonant means, means adjacent said hollow resonant means for providing a constant magnetic field within said hollow resonant means extending along and parallel to said path, means coupled to said hollow resonant means for energizing said hollow resonant means to establish an alternating electric field therein normal to said path, and means adjacent said cathode means for varying the flow of said electron beam whereby the reso-

nant frequency of said hollow resonant means can be varied.

2. A variable frequency device including a cavity resonator having an opening in the wall thereof, cathode means adjacent and exterior to said cavity resonator for directing a beam of electrons along a path through said opening and into the interior of said resonator, means adjacent said resonator for providing a constant magnetic field within said resonator extending along and parallel to said path, means coupled to said cavity resonator for exciting said resonator to provide an alternating electric field therein normal to said path during operation of said device, and means adjacent said cathode means for varying said electron beam for varying the resonant frequency of said device.

3. A variable frequency reactance device including a cavity resonator having an opening in the wall thereof and a pair of opposed surfaces, cathode means adjacent and exterior to said cavity resonator for directing a beam of electrons along a path extending through said opening and into the interior of said resonator and intermediate said opposed surfaces, means coupled to said cavity resonator for establishing an alternating electric field therein extending between said opposed surfaces, means adjacent said resonator for providing a constant magnetic field within said resonator extending along and parallel to said path, and means adjacent said cathode means for varying the electron beam for varying the reactance and resonant frequency of said device.

4. A resonant device including a cavity resonator of rectangular form and having a pair of oppositely-disposed apertures in the walls thereof lying along an axis of said resonator, and means for changing the resonant frequency of said resonator comprising cathode means adjacent said cavity resonator for directing a beam of electrons along said axis through said apertures, means adjacent said cavity resonator for providing a constant magnetic field within said resonator and extending along said axis, and means coupled to said cavity resonator for exciting said resonator to provide an alternating electric field within said resonator normal to said axis.

5. A variable frequency device according to claim 4, further including means in the path of the beam for varying the electron beam for varying the resonant frequency of said resonator.

6. An electron discharge device comprising a cavity resonator having a normal resonant frequency and including a pair of substantially parallel flat opposed surfaces, means coupled to said resonator for providing an alternating electric field extending between said surfaces within said resonator, means adjacent said resonator for providing a constant magnetic field within said resonator intermediate and extending parallel to said opposed surfaces, and means including a cathode adjacent said resonator for directing a beam of electrons within said resonator along a path parallel to said magnetic field and normal to said electric field during operation of said device for changing the resonant frequency of said device.

7. An electron discharge device comprising a cavity resonator having a normal resonant frequency, means adjacent said resonator for projecting a beam of electrons along a predetermined beam path within said resonator, means adjacent said resonator for establishing a constant magnetic field substantially axially of said beam path within said resonator, means coupled to said resonator for establishing an alternating electric field of said normal resonant frequency within said resonator and transverse to said path whereby during operation of said device the electrons of said beam traverse spiral paths around said beam path within said resonator, and means in the path of said beam for varying said beam to vary the resonant frequency of said resonator.

8. An electron discharge device comprising a cavity resonator having inductance and capacitance determining a normal resonant frequency and including a pair of opposed surfaces, means adjacent said resonator for projecting a beam of electrons within said resonator along a predetermined beam path in the space between said opposed surfaces, means adjacent said resonator for establishing a constant magnetic field substantially axially of said beam path and within said space, means coupled to said resonator for establishing an alternating electric field of said normal resonant frequency extending between said opposed surfaces and transverse to said beam path, whereby during operation of said device the electrons of said beam traverse spiral paths around said beam path

within said space and means in the path of said beam for varying said beam to vary the resonant frequency of said resonator.

9. An electron discharge device comprising a cavity resonator having inductance and capacitance determining a normal resonant frequency and including a pair of opposed surfaces, means including a cathode and a collector positioned adjacent and on opposite sides of said resonator for projecting a beam of electrons along a predetermined beam path within said resonator in the space between said opposed surfaces, means adjacent said resonator for establishing a constant magnetic field substantially axially of said beam path and within said space, and means coupled to said resonator for establishing an alternating electric field of said normal resonant frequency extending between said opposed surfaces and transverse to said path, whereby during operation of said device the electrons of said beam traverse spiral paths around said beam path within said space, and means including a control grid adjacent said cathode for modulating the charge density of said beam to modulate the resonant frequency of said resonator.

10. An electron discharge device comprising a cavity resonator in the form of a rectangular box having inductance and capacitance determining a normal resonant frequency and including a pair of opposed parallel walls, means including a cathode and a collector positioned adjacent and on opposite sides of said resonator for projecting a beam of electrons within said resonator along a beam path substantially parallel with said opposed walls, means adjacent said resonator for establishing a constant magnetic field substantially axially of said beam path and within said space, means including a coupling loop coupled to the interior of said resonator for establishing an alternating electric field of said normal resonant frequency extending between said opposed walls and transverse to said path, whereby during operation of said device the electrons of said beam traverse spiral paths around said beam path within said space, and means including a control grid adjacent said cathode for modulating the charge density of said beam to modulate the resonant frequency of said resonator.

11. An electrical system comprising a cavity resonator having a normal resonant frequency, means for projecting a beam of electrons along a predetermined beam path within said resonator, means for establishing a constant magnetic field substantially axially of said beam path and within said resonator, and means for establishing an alternating electric field of said normal resonant frequency within said resonator and extending transverse to said path, whereby the electrons of said beam traverse spiral paths around said beam path within said resonator out of phase with said alternating electric field therein and thus produce a substantial reactive effect upon said resonator to change its resonant frequency.

12. An electrical system according to claim 11, further including means for varying said beam to vary the resonant frequency of said system.

13. An electrical system comprising a cavity resonator having a normal resonant frequency, means for projecting a beam of electrons along a predetermined beam path extending through said resonator, means for establishing a constant magnetic field substantially axially of said path and through said resonator, and means for establishing an alternating electric field of said normal frequency within said resonator and extending transverse to said path, the intensity H of said constant magnetic field, the transit time τ of said electrons through said resonator and the normal resonant frequency f conforming to the relation $\tau(2\pi f - He/m) \approx 4$, where π is 3.1416, and e and m are the charge and mass, respectively, of an electron, whereby the electrons of said beam traverse spiral paths around said beam path through said resonator out of phase with said alternating electric field and thus produce a maximum reactive effect for a given transit time for a given beam current upon said resonator to change its reactance and hence its resonant frequency.

14. An electrical system according to claim 13, further including means for modulating the charge density of said beam for modulating the resonant frequency of said system.

15. A method of changing the reactance and resonant frequency of a cavity resonator without loading the latter, comprising the steps of directing a beam of electrons through said resonator, simultaneously subjecting at least a portion of said beam within said resonator to a transverse alternating electric field and a substantially axial

constant magnetic field and adjusting the transit time of said electrons through said electric field to a value at which the net transfer of energy between said electric field and each electron is zero.

16. A method in accordance with claim 15, further including the step of varying the flow of said beam of electrons.

17. A method of changing the reactance and resonant frequency of a cavity resonator having a normal resonant angular frequency, comprising the steps of directing a beam of electrons along a beam path within said resonator, simultaneously subjecting at least a portion of said beam to a transverse alternating electric field of said resonant frequency and a substantially axial constant magnetic field, and adjusting the intensity of said magnetic field to make He/m slightly different from said resonant angular frequency, where H is the magnetic field intensity and e and m are the electric charge and mass, respectively, of an electron.

18. A method in accordance with claim 17, further including the step of varying the flow of said beam of electrons.

19. A method in accordance with claim 17, wherein the magnetic field intensity H is adjusted relative to the transit time τ of the electrons through said resonator and the normal angular resonant frequency ω to make

$$\tau \left(\omega - \frac{He}{m} \right)$$

approximately equal to 4.

20. An electrical device comprising a cavity resonator normally resonant at a predetermined frequency and having a pair of opposed surfaces, and means for changing the resonant frequency of said resonator comprising means for projecting a beam of electrons along a predetermined initial beam path intermediate said surfaces and means for causing the electrons of said beam to traverse spiral paths around said beam path and intermediate said surfaces, said last named means comprising means coupled to said resonator for establishing an alternating electric field extending between said surfaces and transverse to said path, and means adjacent said resonator for providing a constant magnetic field in the space between said surfaces and substantially parallel to said beam path.

21. An electrical device according to claim 20, further including means in the path of the beam for varying said beam to vary the resonant frequency of said resonator.

22. An electrical system comprising a cavity resonator having a normal resonant frequency, means for projecting a beam of electrons along a predetermined initial beam path within said resonator, means for establishing a constant magnetic field substantially parallel to said beam path and within said resonator, and means for establishing an alternating electric field of said normal resonant frequency within said resonator and extending transverse to said path, the transit time of the electrons within said resonator being adjusted to a value at which the net transfer of energy between said electric field and each electron is zero, whereby the electrons of said beam traverse spiral paths around said beam path within said resonator out of phase with said electric field therein, producing a substantial reactive effect upon the resonator to change its resonant frequency, without loading the resonator.

23. In combination, a cavity resonator having a pair of opposed surfaces, and means for varying the impedance of said cavity resonator comprising means for establishing an alternating electric field extending between said surfaces within said resonator, means for projecting a beam of electrons within said resonator along an initial beam path intermediate said surfaces and transverse to said electric field, means for establishing a constant magnetic field in the space between said surfaces and substantially parallel to said beam path to cause said electrons to traverse spiral paths around said beam path and between said surfaces, and means for varying the flow of said electrons.

24. In combination, a cavity resonator having a pair of opposed surfaces and a normal resonant frequency, and means for variably loading said cavity resonator without affecting its resonant frequency comprising means for establishing an alternating electric field extending between said surfaces within said resonator, means for projecting

a beam of electrons along an initial beam path intermediate said surfaces and transverse to said electric field, means for establishing a constant magnetic field in the space between said surfaces and substantially parallel to said beam path, the intensity H of said magnetic field being adjusted to make

$$\frac{He}{m}$$

substantially equal to $2\pi f$, where e and m are the charge and mass, respectively, of an electron, π is 3.1416, and f is said normal resonant frequency of said resonator, whereby the electrons traverse spiral paths around said beam path and between said surfaces in phase with said electric field at all times, and means for varying the flow of said electrons.

25. An electrical device in accordance with claim 20, comprising a reflector electrode disposed in said beam path on the opposite side of said resonator from said beam projecting means.

26. An electrical device in accordance with claim 25, comprising means for applying a variable voltage to said reflector electrode.

27. The combination recited in claim 23, wherein said last-named means comprises means for varying the charge density of said beam.

28. The combination recited in claim 23, wherein said last-named means comprises means for applying a variable accelerating voltage to said resonator.

29. The combination recited in claim 23, wherein said last-named means comprises a reflector electrode disposed on the opposite side of said resonator from said beam projecting means, and means for applying a variable voltage to said reflector electrode.

30. In a high frequency generator system including a generator, means for providing a constant magnetic field, and an electronic device coupled to said generator and comprising means for projecting an electron beam along an initial path parallel to said magnetic field; the method of variably loading said generator without changing the frequency thereof, comprising the steps of adjusting the intensity of said magnetic field to provide substantially optimum loading of and negligible reactive effect upon said generator, and varying said loading in response to control signals.

31. The method of variably loading a high frequency generator, including the steps of coupling said generator to a cavity resonator, providing a constant magnetic field through said resonator, projecting a loading electron beam through said cavity resonator and along an initial path substantially parallel to said magnetic field, adjusting the intensity of said magnetic field as a function of the operating frequency of said generator to provide maximum loading and negligible reactive effect by said electron beam, and varying the energy-absorbing ability of said beam to vary the loading of said generator.

32. A high frequency system including a generator adapted to provide high frequency oscillations, a variable-conductance electron beam device coupled to said generator, said device comprising means for projecting a beam of electrons along an initial beam path, means for providing a constant magnetic field parallel to said beam path, the electron rotation frequency of said magnetic field being substantially equal to the angular frequency of said oscillations, and means for varying the conductance of said beam to vary the loading of said generator with negligible frequency modulation thereof.

33. A high frequency system including a cavity resonator, means coupled to said resonator for exciting oscillations therein, means for projecting an electron beam along an initial beam path extending through said resonator, means for providing a constant magnetic field parallel to said beam path, the electron rotation frequency of said magnetic field being substantially equal to the angular frequency of said oscillations whereby said beam loads said resonator with negligible reactive effect thereon, and means for varying the conductance of said beam to vary the loading of said resonator.

34. A magnetron pilot cavity resonator, said resonator having a capacitive gap formed by surfaces therein across which high frequency electric fields are impressed, electron means for varying the effective capacity of said gap, said means including a cathode, an anode, and a grid adjacent said capacitive gap and adapted to pass an electron beam therethrough substantially parallel to said

surfaces whereby the control of the density of said electron beam may be utilized to vary the resonant frequency of said resonator, and means for generating a magnetic field substantially parallel to and including said electron beam.

35. A magnetron pilot cavity resonator, said resonator having a capacitive gap formed by surfaces therein across which a high frequency electric field is impressed, electron means adjacent said capacitive gap for varying the effective capacity of said gap, said electron means including a cathode, an anode, and a control grid, said electron means adapted to pass a beam of electrons through said gap at right angles to said electric field whereby the electron density of said electron beam within said gap may be varied, and a pair of magnet poles for producing a magnetic field parallel to the axis of and including said electron beam whereby said electron beam is stabilized and concentrated in said gap.
